UNITED STATES PATENT OFFICE.

STANLEY W. NICHOLSON, OF TOLEDO, OHIO, ASSIGNOR TO DURA MECHANICAL HARDWARE COMPANY, OF TOLEDO, OHIO, A CORPORATION OF DELAWARE.

WINDOW CONSTRUCTION.

1,404,048.

Specification of Letters Patent. Patented Jan. 17, 1922.

Application filed December 6, 1920. Serial No. 428,643.

To all whom it may concern:

Be it known that I, STANLEY W. NICHOLSON, a citizen of the United States of America, residing at Toledo, in the county of Lucas and State of Ohio, have invented certain new and useful Improvements in Window Construction, of which the following is a specification, reference being had therein to the accompanying drawings.

10 This invention relates to window constructions and more particularly to window constructions employing a vertically slideable window member.

It is the object of the invention to provide an improved weather seal at the top of a chamber which receives a vertically slideable window member in its opened lowered position.

A preferred embodiment of the invention 20 is hereinafter described and illustrated in the accompanying drawing wherein;

Figure 1 is a fragmentary exterior front view of a window construction equipped with the improved weather sealing means;

25 Figure 2 is a vertical cross section of the same.

In these views the reference character A designates a window frame in which the glass plate or window member B is vertically 30 slideable, said plate being adapted in its lowered opened position to enter the chamber C underlying said frame. The bottom edge of the plate B is embraced by a channel forming strip D, the upper edge portion of 35 which is flanged outwardly from the exterior face of the plate B as indicated at E to provide a seat for a weather strip F formed preferably of rubber. When the glass plate B is in its closed raised position indicated 40 in the drawings, the weather sealing strip F abuts against a complementary sheet metal weather sealing strip G extending the full width of the window opening, flanged inwardly at its upper edge as indicated at 45 G' so as to form a stop against which the sealing strip F is compressed in the uppermost limiting position of the plate B. A clearance is provided between the flange G' and the plate B and the strip F is flanged 50 upwardly from end to end as indicated at H to provide a closure for said clearance space.

A very positive seal against water entering the chamber C is provided by the described sealing means, the compression to which the strip F is subjected when the sliding plate B is raised insuring a tight water proof joint between said strip and the complementary weather sealing flange G' and the upwardly projecting flange H of the yieldable strip eliminating the presence of any pocket wherein water may lodge to be discharged into the chamber C when the sliding plate is lowered.

What I claim as my invention is:

1. In a window construction, the combination with a vertically slideable glass plate, of a resilient weather strip extended across and directly engaging said glass plate adjacent its lower end and flanged upwardly in proximity to the glass plate, a complementary stationary weather sealing member engageable by said resilient strip in the raised position of the glass plate and having a clearance from the glass plate closed by the flange of said resilient strip in the raised position of the glass plate.

2. In a window construction, the combination with a vertically slideable window member, of a sheet metal channel member embracing the lower edge of said window member, a weather strip carried by the upper portion of said channel member and extending across the window member, and a complementary stationary weather strip engageable by the first mentioned strip in raised position of the window member and so disposed as to provide a clearance space between said stationary strip and window member, the strip carried by the window member having an upstanding projection for entering and sealing said clearance space.

3. In a window construction, the combination with a vertically slideable window member, of a sheet metal channel member embracing the lower edge of said window member and formed with an integral projecting flange, a weather strip seated upon said flange and extending across the window member, and a complementary stationary weather strip engaged by the first mentioned strip in the raised position of the window member and so disposed as to provide a

clearance space between itself and the window member, the strip carried by the window member having an upstanding projection for entering and sealing said clearance space.

5 4. In a window construction, the combination with a slideable glass plate, of a channel-shaped member embracing the lower edge of said plate and formed with a projecting

flange, a weather strip seated in said flange, and a complementary weather strip engageable with the first mentioned weather strip in the closed position of the slideable glass plate and coacting therewith to form a weather-tight joint. 10

In testimony whereof I affix my signature. 14
STANLEY W. NICHOLSON.
